CLAIM

The ornamental design for a chassis assembly for a motorcycle, as shown and described.

DESCRIPTION

FIG. 1 is a side elevational view of one side of a chassis assembly for a motorcycle showing our new design;

FIG. 2 is a top plan view thereof;

FIG. 3 is a bottom plan view thereof;

FIG. 4 is a side elevational view of the other side thereof;

FIG. 5 is a front elevational view thereof;

FIG. 6 is a rear elevational view thereof;

FIG. 7 is a front perspective view thereof;

FIG. 8 is a rear perspective view thereof; and,

FIG. 9 is a side elevational view thereof on a reduced scale shown in position of use on a motorcycle, which is shown in broken lines for illustrative purposes only and forms no part of the claimed design.
